DESIGN FOR A CABINET SINK

Lee C. Love and Parke F. Jones, Columbus, Ohio,
assignors to The Ebcо Manufacturing Co.,
Columbus, Ohio, a corporation of Ohio

Application September 2, 1936, Serial No. 64,695

Term of patent 7 years

To all whom it may concern:

Be it known that we, Lee C. Love and Parke F. Jones, citizens of the United States and residents of the city of Columbus, in the county of Franklin and State of Ohio, have invented a new, original, and ornamental Design for a Cabinet Sink, of which the following is a specification.

In the accompanying drawing, which forms part of this specification,

Fig. 1 is a perspective front elevation of a cabinet sink embodying our invention, the dotted lines indicating a typical cabinet with which the sink may be associated in use; and

Fig. 2 is a perspective view of the top portion of the cabinet sink, a fragmentary portion only of the cabinet being shown for convenience of illustration.

As indicated by the dotted lines, it is contemplated that the sink will ordinarily be associated with a cabinet of some sort, the full lines indicating the dominating features of the design, which reside in the sink proper.

We claim:

The ornamental design for a cabinet sink, as shown and described.
